Primary Examiner — Barbara Fox*Assistant Examiner* — Jamaal Rasheed(74) *Attorney, Agent, or Firm* — James Creighton Way(57) **CLAIM**

The design for a roof vent, as shown and described.

DESCRIPTION

FIG. 1 is a top, right perspective view of a roof vent showing the new design.

FIG. 2 is a bottom, right perspective view thereof.

FIG. 3 is a right side view thereof.

FIG. 4 is a left side view thereof.

FIG. 5 is a front view thereof.

FIG. 6 is a rear view thereof.

FIG. 7 is a top view thereof; and,

FIGS. 8-11 are perspective views from the top, right side, left side and rear of the roof vent shown in FIGS. 1-7. The short-short-long dashed lines show shading and contour of the roof vent.
